[57] CLAIM

The ornamental design for a fetal lung maturation tester, as shown.

DESCRIPTION

FIG. 1 is a top rear perspective view of a fetal lung maturation tester showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a right side elevational view thereof; and

FIG. 7 is a left side elevational view thereof.
